ELECTRICAL APPARATUS

Claude L. Matthews, Theodore Birkenmaier, and
Marion M. Birkenmaier, St. Louis, Mo., assign-
ors to W. N. Matthews Corporation, St. Louis,
Mo., a corporation of Missouri

Application October 7, 1939, Serial No. 298,448

7 Claims. (Cl. 200—127)

This invention relates to electrical apparatus, and with regard to certain more specific features, to electrical line protection apparatus.

Our invention is an improvement upon the apparatus disclosed in the patent application of Claude L. Matthews, Serial No. 293,167, filed September 2, 1939, for Electrical apparatus.

Among the several objects of the invention may be noted the provision of improved means for obtaining resiliency in the horizontal supporting arm of the apparatus disclosed in said application; the provision of apparatus of this class which will predeterminedly limit downward movement of said arm, and which will provide for controlled upward movement; and the provision of apparatus of the class described which is simple in construction and reliable in operation. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which are illustrated two of various possible embodiments of the invention:

Fig. 1 is a top plan view of one form of the invention;

Fig. 2 is a side elevation of Fig. 1;

Fig. 3 is a view similar to Fig. 2, showing a modification;

Fig. 4 is a fragmentary plan view of a hinged joint of Fig. 3; and,

Fig. 5 is a horizontal section taken on line 5—5 of Fig. 3.

Similar reference characters indicate corresponding parts throughout the several views of the drawing.

In Figs. 8-10 of said Matthews application, there is shown a construction wherein a fuse holder is dependently supported within a socket arranged at the end of a flexible cantilever arm which extends from an insulator support. The present invention relates to this general type of support, with improvements.

Referring now more particularly to Fig. 1 herein, there is shown at numeral 1 a line wire carried upon an insulator 3, the insulator being suitably supported. The line wire 1 is held to the insulator by means of suitable anchor wires 7.

A U-bolt 9 surrounds the insulator and in clamping cooperation with a saddle portion 11 55

serves as a support for the parts hereinafter described.

Extending from the saddle 11 in Figs. 1 and 2 is shown a rigid, horizontal extension 13 having a downwardly sloping tongue 15 at its end. Above this extension 13 is a second relatively rigid extension 17 having a curved lower face 19. The rigid extensions 13 and 17 are spaced apart a distance at their inner ends great enough 10 snugly to receive between them a co-planar conducting, phosphor-bronze, cantilever leaf-spring 21 which is pivotally anchored by rivets at 23. Otherwise, the spring member 21 has limited freedom between the members 13 and 17 and functions as a cantilever. The spring 21 extends outward (to the right in Figs. 1 and 2) a distance beyond said members 13 and 17. There is riveted at 25 a supporting member 27 which at its lower end forms a socket for a removable 20 depending fuse holder F. The description of said socket and fuse holder F has been set forth in detail in said application and also in United States Patent 2,103,056, dated December 21, 1937, wherein it is claimed per se.

At 29 is provided means for supporting a wire clamp 31 for a shunt conductor 33 which extends to a suitable connection with the line wire 1. The wire 33 constitutes a shunt with respect to the supporting spring 21, and connects between the line wire 1 and the fuse holder F. The latter is free at its lower end except that it is connected to a work circuit by a suitable wire, as desired. The character of the free lower end and the work-circuit wire connection permitting the desired movement is shown for example in said United States Patent 2,103,056. It is to be understood that the portion of the conductor 33 between connection 29 and the line wire 1 is flexible enough to accommodate the motions to be 30 described.

Upon an explosive action occurring in the fuse holder F there arises an upward force on the holder 27 which forces it upwardly, thus flexing the spring 21. The movement is limited by the 45 fact that the spring sequentially contacts increased areas on the curved portion 19 of the member 17 and conforms itself more or less to the shape of that member. After the explosive force has been spent, gravity and return action of the spring cause it to assume the position shown in Figs. 1 and 2. Any vibratory tendency is rapidly damped out. The tongue 15 prevents 50 local stresses at or near the end of the arm 13.

The advantage of the above resilient construc-

tion over that shown in said Matthews application is that the vibratory action is damped out sooner and the support is better.

In Figs. 3-5 is shown an alternative form of the invention in which like numerals designate like parts. In this case there is provided on the saddle portion 11 an inner extension arm 35 which at its end carries a clevis 37. A pin 39 through the clevis 37 serves to form a pivot joint for an outer extension arm 41. The arm 41 at its outer end carries the member 27 which forms the socket-like support for the fuse holder F.

Depending from the inner arm 35 is a first lever arm 43 and depending from the outer arm 41 is a second lever arm 45. These lever arms are biased toward one another by means of a tension spring 47 looped through suitable openings in the arms.

Extending toward one another from the arms 43 and 45 are fingers 49 and 51, respectively; which, as shown in Fig. 5, cooperate at a V-shaped line 55. The hollow V-shape 53 on the finger 49 serves as a guide to receive the solid V-shape 51. This forms positive stop means.

The operation of the alternative form is as follows:

When an expulsion occurs in the fuse F, the upward force exerted upon member 27 causes the outer extending arm 41 to pivot upwardly around the pin 39. This causes separation (or rotary angling) of the arms 43 and 45, with a consequent stretching and tensioning of the spring 47. At the same time, the guide members 53 and 51 are separated. After the force of the expulsion has been spent, the contracting action of the spring 47 draws down the arm 41 and causes the portion 51 to be guided by and seat in the portion 53. As in the form of the invention shown in Figs. 1 and 2, the form shown in Figs. 3-5 provides for a substantial limitation upon the downward motion of the part after an explosive action.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

We claim:

1. In apparatus of the class described, an upper support for a depending expulsion fuse, the support being adapted to receive the reaction due to expulsion, comprising a laterally extending cantilever arm formed of a spring, means for anchoring said arm at one end, and a rigid member located above the arm and co-planar at one region and diverging therefrom, whereby the arm is limited in its springing action by backing from said diverging member during expulsion.

5 2. In apparatus of the class described, an upper support for a depending expulsion fuse, the support being adapted to receive the reaction due to expulsion, comprising a laterally extending arm formed of a leaf-spring, means for anchoring said arm at one end, a relatively rigid laterally extending support below the arm, and a diverging rigid member located above the arm but co-planar at one point, whereby the arm is normally supported but its springing action is limited by backing from said diverging member during expulsion.

10 3. In apparatus of the class described, an upper support for a depending expulsion member, the support being adapted to receive the reactive force of expulsion, comprising an inner arm, a pivoted outer arm for said supporting member, depending arms respectively from said inner and outer arms, spring means joining said depending arms, and positive stop means between said depending arms.

15 4. In apparatus of the class described, an upper support for a depending expulsion member, the support being adapted to receive the reactive force of expulsion, comprising an inner arm, a pivoted outer arm for said supporting member, depending spring means tensioning said depending arms, and positive stop means limiting said tensioning action.

20 5. In apparatus of the class described, an inner, laterally extending arm, an outer, laterally extending arm pivoted thereto, said last-named arm having an upper support for a depending explosive fuse holder at its outer end, depending arms extending downwardly respectively from said laterally extending arms, a tensioned coil spring biasing said depending arms toward one another, cooperating stop means extending from the depending arms and having cooperating guide surfaces for effecting a limiting stop.

25 6. Line protection apparatus comprising a cantilever member, said cantilever member being normally biased to a downward position, a depending fuse holder supported thereby, and stop means for substantially definitely determining the downward position of the cantilever member in response to the weight of said depending fuse holder.

30 7. Line protection apparatus comprising a cantilever member, said cantilever member being normally biased to a downward position, a depending fuse holder supported thereby, stop means for substantially definitely determining the downward position of the cantilever member in response to the weight of said depending fuse holder, and means for substantially definitely determining the upward motion of the cantilever member in response to its fuse action in the fuse holder.
